BRASSIÈRE

André Silvain, Roubaix, France

Application April 16, 1947, Serial No. 741,816
In France November 26, 1942Section 1, Public Law 690, August 8, 1946
Patent expires November 26, 1962

2 Claims. (Cl. 2—42)

1

This invention relates to brassières. It has already been proposed to make up those parts of brassières that are required to permit a degree of extension from bias materials, which is slow and also expensive particularly by reason of the resulting losses of material.

Further, it has been proposed to bind the edges of such parts by means of woven bands known as ribbon or serge. The chief disadvantage of such bands is that they are not extensible so that the required effect of stretching of the brassières is not achieved, and consequently the wearer of the brassière is hurt or made uncomfortable when the brassière is closely fitted. Moreover, such bands cannot be applied to the edges of highly curved parts, particularly around the breast pockets, without providing in the bands numerous pleats or darts which complicate the work and have an ungraceful effect.

Attempts have been made to replace these woven bands by bands of elastic fabric, but in addition to the latter having practically unlimited elasticity and thereby tending to the tearing of the underlying fabric, it was not possible for reasons of presentability and good taste to apply them over the whole length of the front parts of the brassière that are subject to stretching, because those parts would require to be gathered to accommodate themselves to the stretching of the elastic binding.

The present invention provides an improved brassière by which these various disadvantages are avoided.

A brassière according to the invention is characterised in that it is provided around, at the 35 edge of, or on the front parts intended to fit the curved form, with one or more knitted bands of any suitable textile secured to the base material of the brassière by an extensible stitched seam, either of fast stitches in a zig-zag or lozenge shaped course, or of inherently extensible stitches such as zig-zag stitches or chain stitches. The bands may be knitted on a rectilinear or circular frame in chain-stitch or lock-stitch (interlock).

This novel application to brassières of knitted bands, while reinforcing edge-bound parts, allows them an extensibility not obtainable with bands of woven tape, the said extensibility moreover having the notable characteristic of being limited to that proper to knitted fabric, which obviates 50 any possibility of tearing of the base fabric (tulle, lace, cambric or the like) of the brassière.

According to a modification, the same effect is obtained by binding, surrounding or covering those parts of the brassière that require to accom-

2

modate themselves to a degree of extension, with plaited or braided bands, which, as regards extensibility, are substantially equivalent to knitted bands.

By reason of their extensibility in breadth as well as in length, knitted or plaited or braided bands can be applied without pleats or darts to parts of high curvature, particularly to the peripheries of the breast pockets.

The improved brassière affords perfect modelling to the breasts even and especially when they are of a fullness greater than the relaxed pockets, and this without any risk of cutting the flesh.

The edge-binding may be applied along the lower edge or waist-band of the brassière, along the upper edge at the back and about the whole peripheries of the pockets; the entire surface of the latter may even be covered with a knitted band, for example, coiled in a spiral.

By way of example, an embodiment of the invention is illustrated on the accompanying drawing whereon the single figure shows the brassière flat, as seen from the inner side.

Reference *a* designates the or one of the bands, 25 knitted from any textile (cotton, wool, rayon, fibranne, etc.) and applied as edging or on the parts intended to fit closely the curved form. In the example, these bands are shown applied along the lower edge or waist-band *c* of the brassière and around the breast pockets *b* whence they can be prolonged to form the shoulder straps.

The obverse surface of each pocket may also, as shown in chain-dotted lines at *a*¹, be entirely covered by means of such a band, for example, coiled in a spiral, contiguous or otherwise, or equally by means of several circular bands.

Moreover, a band *a* can also be provided along the upper edge of the back *d* and continue along the transverse edge *d*¹ of the back portions.

The bands *a* are secured to the base material *f* of the brassière (of tulle, lace, cambric or other material, reinforced in places, for example at *s*, by satin) by extensible stitched seams *p*, either in fast stitches following a zig-zag or lozenge shaped path, executed by means of an ordinary sewing machine, or in stitches individually extensible, executed with an embroidery or chain-stitching machine, or any other modern machine, as commonly employed in the hosiery trade, making extensible stitches.

What has been stated concerning the arrangement and securing of knitted bands on the base fabric of the brassière, applies also to plaited and braided bands. They can be applied particularly along the lower edge or waist-band of the

brassière, along the edges of the back, about the peripheries of the breast pockets and even over the surface of the latter. And they too can be secured on the base fabric of the brassière by extensible stitched seams, either of fast stitches following a zig-zag or lozenge shaped course, formed by means of an ordinary sewing machine, or of stitches inherently extensible, formed with an embroidery stitch machine or a chain stitch machine.

It is to be understood that the present invention would be neither exceeded nor derogated by the fact of applying to brassières knitted bands presenting intercalated parts knitted from elastic thread, instead of unitary bands of knitted tape. 15

I claim:

1. In a brassière a breast supporting unit comprising in combination a breast pocket; a knitted binding band having a certain limited stretchability in longitudinal direction of said band; and 20 extensible stitches extensibly securing said binding band along the edge of said breast pocket circumferentially encircling at least part of said breast pocket.

2. A brassière comprising in combination two 25 breast pockets secured at their inner edges to

each other; two body portions each secured at one end to the outer edge of one of the breast pockets; means for attaching said body portions at their other ends to each other; and two binding bands having a certain limited stretchability in longitudinal direction, each of said bands extensibly secured along the edge of one of the breast pockets circumferentially encircling the same and having a free end portion secured at its other end to the rear end of the corresponding body portion so as to form a shoulder strap.
